RECEPTACLE HOLDER

Thomas B. Allen, Minneapolis, Minn.

Application December 23, 1946, Serial No. 717,880

5 Claims. (Cl. 248—149)

1

My invention relates to improvements in receptacle holders for garbage and refuse cans and similar containers, an object of the invention being to provide a simple, durable, sightly and relatively inexpensive holder of the instant nature adapted to hold a receptacle in an upright position, more or less above the ground, as desired, and secure against being tipped over accidentally or by dogs, children, pranksters or the like.

Another object of the invention is to supply a receptacle holder of the instant nature in which the parts are duplicated, in large measure, and in which the various parts are capable of being stored and shipped compactly in disassembled form and readily assembled at a given site to accord with the size of the particular receptacle to be held thereby.

A further object of my invention is to provide a receptacle holder in which clamps applied to posts serve to secure can-supporting means thereto.

More specifically, it is an object of my invention to provide a holder of the instant nature wherein the clamps are vertically adjustable on the posts and adapted to bind the can-supporting means between the same and said posts.

Another object of the invention is to furnish a can-supporting member in the form of a hoop and to construct the clamps in a manner to crimp portions of the hoop about the posts and thereby lend rigidity to the holder structure, an additional object of the invention being to supply such a hoop in form enabling it to be adjusted circumferentially to fit any of various sizes of cans.

Other objects of the invention reside in the novel combination and arrangement of parts and in the details of construction hereinafter illustrated and/or described.

In the accompanying drawing, Fig. 1 is a perspective view of a form of receptacle holder constructed in embodiment of my invention; Fig. 2 is an enlarged sectional view taken on the line 2—2 of Fig. 1 and fragmentarily showing one of the posts with its clamps securing the can-supporting members thereto, portions of said clamps being broken away to reveal features of construction otherwise concealed; Fig. 3 is a detail sectional view taken as on the line 3—3 of Fig. 2, showing the upper clamp on the post and the overlapped ends of the hoop-forming strap crimped upon each other about the post and gripped between said post and the seat of the clamp; Fig. 4 is also a detail sectional view, the

2

same being taken on the line 4—4 of Fig. 2 and showing the lower clamp on the post and a can-supporting member gripped to the post by said clamp; and Fig. 5 is a perspective view of the band which constitutes one of the parts of a clamp.

Reference being had to said drawing, it will be seen that the illustrated form of my invention includes posts A, upper and lower clamps B on

10 said posts, a support C in the form of a can-embracing hoop 10 secured to said posts A by said upper clamps B, and supports D secured to said posts by the lower clamps B to provide a footing for a can, as at 11, received within the 15 hoop 10.

The posts A are preferably identical and each thereof may include a tube 12 fitted at its lower end with a point 13 to facilitate the driving of the post into the ground, and may also include 20 a cap 14 fitted to the upper end of the tube 12 to protect said tube against the battering blows of an instrument employed in driving the post into the ground.

Preferably, the clamps B are identical, each 25 thereof including a band 15 made from a strap bent into the form best seen in Fig. 5 to provide a seat 16 curved to conform substantially with the side of a post, arms 17 extending from said seat 16 at either side thereof to embrace such 30 post, and terminal ears 18 overlapping each other opposite said seat 16 to provide a mount for a clamping screw 19 which comprises another part of the clamp. The stem of the clamping screw 19 is received in registering openings 20 formed in 35 the terminal ears 18 of the clamp-band 15 and is threaded into a nut 21 located inside of the mount formed by said ears 18. In this connection, it is to be noted that said arms 17 converge toward said terminal ears 18 and form obstructions 40 which keep the nut 21 from turning when the clamping-screw 19 therein is turned.

In each of the upper clamps B, the arms 17 of the clamp-band 15 are formed with slots or eyes 22 offset from the seat 16 to receive the hoop 10. 45 This hoop 10 consists of a strap adapted to be circularly bent and threaded through the slots 22 of the upper clamps B with its ends overlapped within such slots 22 of one of said clamps.

The lower clamps B may be duplicates of the 50 upper clamps B, but, since can-supporting means in form other than that of a hoop are secured to the posts A by said lower clamps B, the slots 22 in the arms 17 of the clamp-bands 15 may be omitted, if desired. Such other form of can-supporting means comprises the supports D, there

being one thereof for each post A, each consisting of a strip, one end portion of which provides a leg 23 to be gripped between a post A and the seat 16 of a clamp B, and the other end portion, bent at right angles to said first end portion, provides a rest 24 for the bottom of a can embraced within the hoop 10 gripped to the posts A by the upper clamps B.

The parts of my improved holder, namely, the posts A, the clamps B, lower supports D and hoop 10, in a roll or flattened out straight, are conveniently stored or transported in compact form. To assemble and install said parts for use, the user threads two of the clamps B, either side uppermost, on each post A and thereupon drives the lower ends of said posts into the ground equally spaced apart about a circle of slightly greater diameter than that of the can or other receptacle to be accommodated in the holder. The upper clamps B are then angularly positioned relative to the posts A with the seats 16 of said clamps adjacent the inner sides of the posts. Then, the strap which forms the hoop 10 is threaded through the slots 22 in said upper clamps B, said strap being shaped circularly to bring its ends into overlapping relation within the slots 22 of one of said clamps B. Obviously, any excess in the length of the strap forming the hoop 10 will be accommodated in the overlap at the ends thereof. Said relative positioning of parts brings the clamping-screws 19 into position to be turned against the outer sides of the posts A. Disposing the hoop 10 and upper clamps B at the desired elevation, the assembler tightens the clamping-screws 19, thereby causing the hoop 10 to be firmly gripped between the seats 16 of the clamps B and the inner sides of the posts A. Firmness of the grip between the hoop 10 and posts A is enhanced by crimps 25 which are pressed into said hoop 10 upon the squeezing thereof between the clamp-seats 16 and posts A, said crimps 25 occurring not only at points of single thickness of the hoop-forming strap, but also at the point of double thickness thereof (Fig. 3) where the ends of the strap overlap in the one of said clamps B. Crimped about the posts A, the hoop 10 is securely attached thereto, and, in turn, braces said posts relative to each other. Having fixed the hoop 10 to the posts A, the assembler angularly disposes each of the lower clamps B in correspondence with their upper companion clamps B. One of the supports D is then applied to each of the lower clamps B by inserting the leg 23 of such support between the seat 16 of said clamp and its respective post A so that the rest 24 of such support D will extend radially inward from the post, as shown in Fig. 1. Thereupon, said lower clamps B will be tightened upon the posts A by turning the clamping-screws 19 against said posts. In so fixing said lower clamps B, they will be preferably disposed in elevation to locate the rests 24 of said supports D in a common plane above the ground level. To enhance the firmness with which the legs 23 of the supports D are gripped between the lower clamps B and the posts A, said legs 23 are preferably curved transversely thereof to conform with the curvature of the clamp-seats 16 and posts A.

The can or other receptacle to be held in the erected holder is lowered through the hoop 10 and bottomed upon the rests 24. In such position, the can is supported above the ground surface and, while it is readily liftable out of the holder, it is thereby securely held against being tipped over.

In installations of my holder, wherein a relatively close fit between the can and posts is obtained, the supports D may be dispensed with and the lower clamps B angularly disposed in opposition to the positions shown in Fig. 1. Thus disposed, the arms 17 of said clamps B will in themselves serve as rests for the bottom of the can or other receptacle.

Changes in the specific form of my invention, 10 as herein described, may be made within the scope of what is claimed without departing from the spirit of my invention.

Having described my invention, what I claim as new and desire to protect by Letters Patent is:

- 15 1. In a receptacle holder, a plurality of posts, a hoop adapted to be supported by said posts and to embrace the receptacle to be held, clamps for mounting the hoop on said posts, there being one clamp for each post, each clamp consisting of a band encircling its respective post, a portion of said band constituting a seat for disposition adjacent the inner side of the post, said band having openings therein offset from said seat at opposite sides thereof for the reception of a portion of said hoop at a location between said seat and the inner side of said post, and a clamping screw carried by the band opposite said seat and engageable with the outer side of the post to tighten the clamp and cause said portion of said hoop to be crimped about the post and gripped between said seat and said post.
- 20 2. In a receptacle holder, posts, clamps and supports, there being one clamp and one support for each post, each clamp consisting of a clamping screw and a strap, different portions of said strap comprising, respectively, a seat for disposition adjacent the inner side of the post, an arm, and a mount opposite said seat for the clamping screw, said screw being engageable with the outer side of the post, each support consisting of two members disposed at right angles to each other, one member constituting a rest for the receptacle and the other member providing a leg for said first member, said leg being adapted to be received between the seat of its respective clamp and the inner side of its respective post and to be gripped between such seat and post.
- 25 3. In a receptacle holder, a post, a hoop adapted to be supported by the post and, in turn, to embrace and support the receptacle to be held, 30 and a clamp for securing said hoop to said post in various positions thereon longitudinally thereof, said hoop consisting of a strap shaped to bring the end portions thereof into overlapping relationship, said clamp consisting of a nut, a screw threaded in said nut, and a band formed from a strap bent to provide intermediately thereof a seat for disposition adjacent one side of the post, also post-embracing arms extending from the seat and, further, a mount in opposition to said seat comprising the terminal portions of said arms, said portions being oppositely bent relative to said arms into overlapping relation and formed with registering apertures loosely receiving said screw, said nut being backed against said mount between said arms and restrained against rotation by the latter, said arms of said clamp having slots therein offset from said seat at opposite sides thereof for the reception of the overlapped ends of said hoop-forming strap at a location between said seat and said first side of said post, said screw being adapted to be advanced in said nut against the side of the post opposite said first side thereof to tighten the clamp and cause said overlapped portions of said
- 35 4. In a receptacle holder, posts, clamps and supports, there being one clamp and one support for each post, each clamp consisting of a clamping screw and a strap, different portions of said strap comprising, respectively, a seat for disposition adjacent the inner side of the post, an arm, and a mount opposite said seat for the clamping screw, said screw being engageable with the outer side of the post, each support consisting of two members disposed at right angles to each other, one member constituting a rest for the receptacle and the other member providing a leg for said first member, said leg being adapted to be received between the seat of its respective clamp and the inner side of its respective post and to be gripped between such seat and post.
- 40 5. In a receptacle holder, a post, a hoop adapted to be supported by the post and, in turn, to embrace and support the receptacle to be held, 45 and a clamp for securing said hoop to said post in various positions thereon longitudinally thereof, said hoop consisting of a strap shaped to bring the end portions thereof into overlapping relationship, said clamp consisting of a nut, a screw threaded in said nut, and a band formed from a strap bent to provide intermediately thereof a seat for disposition adjacent one side of the post, also post-embracing arms extending from the seat and, further, a mount in opposition to said seat comprising the terminal portions of said arms, said portions being oppositely bent relative to said arms into overlapping relation and formed with registering apertures loosely receiving said screw, said nut being backed against said mount between said arms and restrained against rotation by the latter, said arms of said clamp having slots therein offset from said seat at opposite sides thereof for the reception of the overlapped ends of said hoop-forming strap at a location between said seat and said first side of said post, said screw being adapted to be advanced in said nut against the side of the post opposite said first side thereof to tighten the clamp and cause said overlapped portions of said
- 50 6. In a receptacle holder, a post, a hoop adapted to be supported by the post and, in turn, to embrace and support the receptacle to be held, 55 and a clamp for securing said hoop to said post in various positions thereon longitudinally thereof, said hoop consisting of a strap shaped to bring the end portions thereof into overlapping relationship, said clamp consisting of a nut, a screw threaded in said nut, and a band formed from a strap bent to provide intermediately thereof a seat for disposition adjacent one side of the post, also post-embracing arms extending from the seat and, further, a mount in opposition to said seat comprising the terminal portions of said arms, said portions being oppositely bent relative to said arms into overlapping relation and formed with registering apertures loosely receiving said screw, said nut being backed against said mount between said arms and restrained against rotation by the latter, said arms of said clamp having slots therein offset from said seat at opposite sides thereof for the reception of the overlapped ends of said hoop-forming strap at a location between said seat and said first side of said post, said screw being adapted to be advanced in said nut against the side of the post opposite said first side thereof to tighten the clamp and cause said overlapped portions of said
- 60 7. In a receptacle holder, a post, a hoop adapted to be supported by the post and, in turn, to embrace and support the receptacle to be held, 65 and a clamp for securing said hoop to said post in various positions thereon longitudinally thereof, said hoop consisting of a strap shaped to bring the end portions thereof into overlapping relationship, said clamp consisting of a nut, a screw threaded in said nut, and a band formed from a strap bent to provide intermediately thereof a seat for disposition adjacent one side of the post, also post-embracing arms extending from the seat and, further, a mount in opposition to said seat comprising the terminal portions of said arms, said portions being oppositely bent relative to said arms into overlapping relation and formed with registering apertures loosely receiving said screw, said nut being backed against said mount between said arms and restrained against rotation by the latter, said arms of said clamp having slots therein offset from said seat at opposite sides thereof for the reception of the overlapped ends of said hoop-forming strap at a location between said seat and said first side of said post, said screw being adapted to be advanced in said nut against the side of the post opposite said first side thereof to tighten the clamp and cause said overlapped portions of said
- 70 8. In a receptacle holder, a post, a hoop adapted to be supported by the post and, in turn, to embrace and support the receptacle to be held, 75 and a clamp for securing said hoop to said post in various positions thereon longitudinally thereof, said hoop consisting of a strap shaped to bring the end portions thereof into overlapping relationship, said clamp consisting of a nut, a screw threaded in said nut, and a band formed from a strap bent to provide intermediately thereof a seat for disposition adjacent one side of the post, also post-embracing arms extending from the seat and, further, a mount in opposition to said seat comprising the terminal portions of said arms, said portions being oppositely bent relative to said arms into overlapping relation and formed with registering apertures loosely receiving said screw, said nut being backed against said mount between said arms and restrained against rotation by the latter, said arms of said clamp having slots therein offset from said seat at opposite sides thereof for the reception of the overlapped ends of said hoop-forming strap at a location between said seat and said first side of said post, said screw being adapted to be advanced in said nut against the side of the post opposite said first side thereof to tighten the clamp and cause said overlapped portions of said

hoop-forming strap to be crimped one upon the other about the post and gripped between said seat and said post.

4. In a receptacle holder, a post, a mounting clamp applicable to the post, said clamp consisting of a nut, a screw threaded in the nut, and a band comprising a strap bent to provide intermediately thereof a seat for disposition adjacent one side of the post, also post-embracing arms extending from the seat, and a mount in opposition to said seat comprising the terminal portions of said arms, said terminal portions being oppositely bent relative to said arms into overlapping relation and formed with registering apertures loosely receiving said screw, said nut being backed against said mount between said arms and restrained against rotation by the latter, and a support for a receptacle, said support having a portion thereof receivable between said seat and post, said screw being adapted to be advanced in said nut against the side of said post opposite said first side thereof to tighten the clamp and grip said portion of said support between said seat and post.

5. In a receptacle holder, a post, a hoop adapted to be supported by said post and to embrace a receptacle to be held, said hoop consisting of a strap bent to bring the end portions thereof

into overlapping relationship, and a clamp for mounting the hoop on said post, said clamp consisting of a band encircling said post, a portion of said band constituting a seat for disposition adjacent one side of the post, said band having openings therein offset from said seat at opposite sides thereof for the reception of the overlapped end portions of said strap at a location between said seat and said side of the post, and a clamping screw carried by the band opposite said seat and engageable with the side of the post opposite said first mentioned side thereof to shift the clamp relative to the post, thereby to cause said overlapped end portions of said strap to be crimped one upon the other about said post and gripped between said seat and post.

THOMAS B. ALLEN.
